UNITED STATES PATENT OFFICE.

CHARLES W. KENNEDY, OF NAMPA, IDAHO.

ROTARY ENGINE.

Application filed August 4, 1922. Serial No. 579,701.

To all whom it may concern:

Be it known that I, CHARLES W. KENNEDY, a citizen of the United States, residing at Nampa, in the county of Canyon and 5 State of Idaho, have invented new and useful Improvements in Rotary Engines, of which the following is a specification.

This invention relates to internal combustion engines and has for its object the 10 provision of a rotary single cylinder engine of the two cycle type which operates on a gyroscopic principle and which therefore overcomes vibration and is very easy running.

15 An important object is the provision of an engine of this character which is air cooled and which therefore has the advantage of eliminating the troublesome water circulating system ordinarily employed for 20 effecting cooling.

Still another object is the provision of an engine of this character which is provided with a centrifugally operated automatic speed control device in addition to a manual 25 control, the automatic device being capable of adjustment for varying the engine speed.

A further object is the provision of an engine of this character having novel fuel inlet means and novel mode of treatment for the 30 exhaust.

An additional object is the provision of an engine of this character which will be simple and inexpensive in manufacture, 35 easy to operate and control, efficient and durable in service and a general improvement in the art.

With the above and other objects and advantages in view the invention consists in the details of construction to be hereinafter 40 more fully described and claimed, and illustrated in the accompanying drawings, in which:

Figure 1 is a longitudinal section through the engine,

45 Figure 2 is a cross section therethrough looking at the distributor,

Figure 3 is a cross section looking toward the fan,

50 Figure 4 is a cross section taken through the governor mechanism,

Figure 5 is a cross section taken through the exhaust manifold,

55 Figure 6 is an enlarged detail view of the piston,

Fig. 7 is a detail view of the inlet valve and

Figs. 8 and 9 are detail views.

Referring more particularly to the drawings I have shown the engine as consisting of a suitable base 10 from which rise uprights 11 formed with bearings 12. The engine proper is mounted between these uprights and includes a main casting 13 to the center of one side of which is bolted a cylinder 14 which is provided with peripheral fins 15 to facilitate radiation of the heat so as to effect the proper cooling. Bolted onto the other side of the main casting is a housing 16 having a hub extension 17. The main casting 13 is greatly enlarged 70 to define a fly wheel 18. Carried by the outer end of the cylinder 14 is a stub shaft 19 which is journaled in one bearing 12 while extending through the housing 16 and hub 17 is a hollow shaft 20 which is angular 75 in shape and preferably square in cross section so as to be stationary. The numeral 21 designates roller bearings, one of which is located within one bearing 12 and the other of which is located within the hub 17 and the rollers are preferably conical to take up 80 end thrust.

The stub shaft 19 extends beyond its associated bearing and carries a pulley 22 and also carries a ratchet 23 engageable by a 85 suitable crank 24 for effecting initial rotation of the fly wheel to start the motor.

The ignition consists of a stationary supply disk 25 mounted against one bearing 12 and co-operating with a rotary disk 26 secured upon the stub shaft 19 and having a contact 27 with which is connected a terminal wire 28 leading to a spark plug 29 of ordinary type screwed into a suitable opening in the closed end of the cylinder. Any 90 suitable current supply may be used for feeding current to a contact button 30 on the stationary disk 25 so that a spark will be produced at the terminals of the plug at every revolution of the fly wheel. It should 95 be mentioned that the stationary disk is adjustable so that the spark may be advanced or retarded as occasion may require.

Mounted within the housing 16 is a stationary gear 31 with which meshes a gear 32 105 formed on the underside of an angle plate 33 which is rotatably mounted upon the inner end of the shaft 20 and which is supported by a lug 34 on the shaft 20. The numeral 35 designates a piston which is 110 mounted for reciprocation within the cylinder 14 and which is provided with the usual

packing rings 35 and which has its outer end formed with a deflector 37. Within the piston is a socket 38 within which is engaged a ball 39 on one end of a connecting rod 40 which has its other end provided with a socket 41 engaging a ball pin 42 on the angle plate 33.

The numeral 43 designates a carburetor of any ordinary or preferred type which is connected with the outer end of the hollow shaft 20 and which is provided with a throttle control rod 44 regulated by means of a lever 45 pivoted on the adjacent support 11 as shown at 46. Mounted within the inner end of the hollow shaft 20 is an inwardly opening poppet valve 47 which controls the inlet of fuel mixture into the housing and cylinder.

The numeral 48 designates an exhaust manifold which is of ring like formation with its side toward the fly wheel formed with an annular slot 49. This manifold is held stationary by brackets 50 secured to the adjacent upright 11 as clearly shown. The cylinder wall is formed with a port 51 which communicates with a right angularly shaped pipe 52 which leads into passages 53 formed through the fly wheel. Leading from the other end of this passage is a pipe 54 which extends into the manifold 48, the slot 49 permitting such passage. At an opposite point the cylinder wall is formed with an inlet port 55 which communicates with a pipe 56 extending to a passage 57 formed through the fly wheel and communicating with the inner of the housing 16. It should be mentioned that the exhaust manifold is provided with an outlet pipe 58 leading to any suitable muffler.

40 Mounted within the fly wheel at the hollow side thereof is a fan 59 which of course operates to circulate the air about the engine and consequently effect cooling thereof at all times.

45 Mounted upon the hub 17 is a sleeve 60 formed with ribs 61 which define a groove 62, and also formed with a separate rib 63. Pivoted on the outer side of the housing 16 are fly balls 64 which have fingers 65 engaging within the groove 62. It should be mentioned that the sleeve 60 is slidable upon the hub. Connected with the throttle control rod 44 is a fork 66 which engages the single rib 63.

55 In the operation of the device fuel mixture passes from the carburetor through the hollow shaft 20, past the valve 47 into the housing 16 and then through the passage 57 and pipe 56 through the inlet port 55 into the cylinder 14, this action occurring on the suction stroke of the piston. When the piston passes beyond the inlet port 55 and closes it the mixture in advance of the piston will be compressed and when the piston reaches its outermost position the charge

will be ignited by the spark plug 29 so that the piston will be forced back and given its working stroke. As the piston is thus reciprocated the connecting rod will operate to rotate the angle plate 33 and gear 32. 70 Owing to the fact that the gear 31 is stationary this will result in rotation of the main casting constituting the fly wheel, together with the cylinder and also the housing, all of these parts acting as a unit. During the operation of the piston, upon reaching the end of its working stroke the burnt gases tending to expand will be deflected by the deflector 37 into and through the outlet port 51, pipe 52, passage 53, pipe 54 into the ring like exhaust manifold 48 and thence to the muffler, not shown, through the pipe 58. This is the complete cycle of operations. It is obvious that rotation of the fan 59 will operate to cool the motor and that the fins 85 15 on the cylinder act for the same purpose.

The speed is controllable manually by moving the lever 45 to vary the position of the rod or arm 44. However the speed is automatically controllable by means of the 90 fly balls 64 which move outwardly under the influence of centrifugal force so that the arms or fingers 65 will move the sleeve 60 longitudinally whereupon the rib 63 engaging the fork 66 will operate to shut down 95 the throttle to a greater or less extent.

From the foregoing description and a study of the drawings it will be apparent that I have thus provided a simply constructed and consequently inexpensive single cylinder rotary gasoline engine in which the gyroscopic principle is well applied to eliminate the usual vibration and to make a very smooth running and silently operated engine. The various features of control and cooling have been dwelt upon above and it is believed that the full advantages and benefits to be derived will be readily apparent to one skilled in the art without need for further elaboration. 105 110

While I have shown and described the preferred embodiment of the invention it is of course to be understood that I reserve the right to make such changes in the form, construction and arrangement of parts as will not depart from the spirit of the invention or the scope of the subjoined claim. 115

Having thus described my invention I claim:

A rotary engine comprising a fixed fuel supply pipe having an offset end portion provided with a valve controlled port, a gear wheel journaled upon the fuel supply pipe and disposed in a plane at an acute angle to the axis of the said pipe, a housing journaled upon the supply pipe, a gear wheel fixed to the housing and concentrically mounted with relation to the pipe and meshing with the first mentioned gear wheel, the housing receiving both of the said gear 120 125 130

wheels, a fly wheel fixed to the housing and arranged concentrically with relation to the supply pipe, a cylinder fixed to the fly wheel and disposed with its axis in alinement with the axis of the supply pipe, a conduit passing transversely through the fly wheel and communicating at one end with the interior of the housing and at its other end with the interior of the cylinder, a piston mounted

for sliding movement in the cylinder and a piston rod pivotally connected at one end with the first mentioned gear wheel at the point concentrically thereof and connected at its other end with the piston for universal movement with relation thereto.

15

In testimony whereof I affix my signature.

CHARLES W. KENNEDY.
